UNITED STATES PATENT OFFICE

IRVING W. FARQUHARSON, OF MEDIA, PENNSYLVANIA

DESIGN FOR A COMBINATION SPOON AND SCRAPER OR SIMILAR ARTICLE

Application filed July 22, 1930. Serial No. 36,440. Term of patent 14 years.

To all whom it may concern:

Be it known that I, IRVING W. FARQUHARSON, a citizen of the United States, residing at Media, in the county of Delaware and State of Pennsylvania, have invented a new, original, and ornamental Design for a Combination Spoon and Scraper or Similar Article, of which the following is a specification, reference being had to the accompanying drawings, forming part thereof.

Fig. 1 is a side elevation of a combination spoon and scraper or similar article; and Fig. 2 is a perspective view of the same.

I claim:

The ornamental design for a combination spoon and scraper or similar article substantially as shown.

IRVING W. FARQUHARSON.
